ENGINE STARTERS

LeRoy T. Bossard and Wade A. Eskridge, Tulsa, Okla.

Application November 25, 1955, Serial No. 548,961

5 Claims. (Cl. 74—8)

This invention relates to starting devices for large engines, and more particularly, but not by way of limitation, to an improved power unit provided with friction type power take off means for engaging the fly wheel of a large engine to start said large engine. This application is a continuation-in-part of applicants' co-pending application Serial No. 403,580, entitled "Engine Starter" and filed on January 12, 1954, now Patent No. 2,725,752.

Heavy duty power plants, such as used in the oil industry, are normally provided with a large horizontal engine for operation thereof. These large engines are usually provided with a large fly wheel which must be rotated in order to start the engine. It is very difficult and often dangerous to initiate the rotation of the fly wheel by manual means. The present invention, therefore, contemplates a simple and efficient engine starter which comprises a small easily started engine having a friction type power take off adapted to intermittently engage the fly wheel of the large engine. The rotation of the friction pulley of the power take off transmits rotation or torque to the fly wheel of the large engine upon contact therewith for facilitating the starting thereof. The friction pulley may be readily moved into and out of engagement with the large fly wheel by means of an easily actuated foot lever. Upon starting of the large engine, the friction pulley may be moved away from the fly wheel by means of the foot lever, and the operation of the small engine may be ceased. Thus, the present invention provides a simple and efficient engine starter which is durable and economical in operation and construction.

It is an important object of this invention to provide a novel starter mechanism for initiating the operation of large engines in an expedient and safe manner.

It is another object of this invention to provide a starter mechanism for large engines whereby a friction surface may be readily moved into contact with the fly wheel of a large engine for initiating rotation thereof for starting of the large engine in a simple and efficient manner.

It is still another object of this invention to provide a starter mechanism for large engines which is of a simple and compact construction for facilitating the manipulation and operation thereof.

It is a further object of this invention to provide an improved starter mechanism for initiating the operation of large engines which is economical and durable in construction and simple and efficient in operation.

Other objects and advantages of the invention will be evident from the following detailed description, read in conjunction with the accompanying drawings, which illustrate my invention.

In the drawings:

Figure 1 is a fragmentary top plan view showing the fly wheel of a large horizontal engine and improved starting means embodying the present invention, the starting means being shown located adjacent the fly wheel.

2

Figure 2 is a vertical cross sectional view taken on line 2—2 of Fig. 1.

Figure 3 is an enlarged vertical cross sectional detail view taken on line 3—3 of Fig. 1 with portions shown in dotted lines for purposes of illustration.

Figure 4 is an enlarged vertical cross sectional detail view taken on line 4—4 of Fig. 2.

Referring to the drawings in detail, reference character 10 refers in general to a relatively large horizontal engine having a relatively large fly wheel 12 which must be rotated in order to start the engine 10. A relatively small air cooled engine, generally designated at 14, is disposed adjacent the fly wheel 12. The engine 14 is rigidly secured to a channel member 16 in any suitable manner, such as bolts 15. The channel member 16 is pivotally secured between a pair of spaced angle iron side members 18 and 20 which are secured to the floor adjacent the engine 10. The members 18 and 20 extend substantially parallel to the plane of the fly wheel 12 and are preferably spaced apart by means of a pair of slat members 22, only one of which is shown, disposed at the opposite ends of the side members 18 and 20. A transverse pivot bar 24 extends between the side members 18 and 20 and is suitably secured to the channel member 16 to provide for pivotal movement thereof with respect to the side members 18 and 20. Thus, the small air cooled engine 14 is pivotally mounted for rotation in a plane parallel to the plane of the fly wheel 12 around the axis defined by the transverse shaft 24, said shaft 24 being located adjacent the left ends of the side members 18 and 20 as viewed in Figs. 1 and 2.

Designated at 26 is a pulley which is mounted on the out put shaft 28 of the small engine 14. The out put shaft 28 is driven in any conventional manner by the small engine 14, preferably through suitable gearing to provide a substantial speed reduction between the crank shaft of the engine 14 and the out put shaft 28, as for example, a six-to-one speed reduction. The reduction gearing may be contained in a suitable housing or gear box 30 provided on the engine 14.

The pulley 26 is covered with a friction surface 32 which may comprise a rubber covering on the periphery of the pulley. As shown in Figs. 1 and 2, the pulley 26 is located sub-adjacent to and in the same plane as the large fly wheel 12 and may be elevated into contact with the peripheral surface of the fly wheel 12 by lifting the engine 14 and rotating the engine upwardly around the shaft 24.

The side members 18 and 20 preferably extend beyond the channel member 16 at the right end thereof, as seen in the drawings, to receive a transverse shaft 34 journaled therebetween. A lever arm 36 is rigidly secured to one end of the shaft 34. The lever arm 36 is provided with a suitable foot pedal 38 at its outer extremity to facilitate operation thereof as will be hereinafter set forth. An arm member 40 is rigidly secured to the shaft 34 substantially medial thereof in a position underlying the top flange of the channel member 16. The arm 40 is provided with a cam surface 42 (Fig. 3) at one end thereof adjacent the channel member 16, and the opposite end thereof is provided with a tapered portion 44 for limiting the rotation of the shaft 34 in one direction as will be hereinafter set forth.

As will be readily apparent from Figs. 2 and 3, when the pedal 36 is depressed as shown by the arrow in Fig. 2, the shaft 34 will be rotated in a clockwise direction, as viewed in Figs. 2 and 3. As the shaft 34 is rotated in a clockwise direction, the cam surface 42 of the arm 40 will contact the channel member 16 for elevation thereof as shown in dotted lines in Fig. 3. Upon sufficient clockwise rotation of the shaft 34, the tapered surface 44 of the arm 40 will contact the cross member 22, as shown

in dotted lines in Fig. 3, for limiting the clockwise rotation of the shaft 34. Thus, accidental disengagement of the cam surface 42 and the channel member 16 is precluded. The elevation of the channel member 16 lifts the motor 14 for rotation in a counterclockwise direction, as viewed in Figs. 2 and 3, thereby bringing the pulley 26 into contact with the periphery of the fly wheel 12. Thus, the friction surface 32 of the rotating pulley 26 engages the fly wheel 12 and transmits torque to the fly wheel 12, causing the fly wheel to rotate whereby the large engine 10 may be started. This is accomplished by depressing the pedal 38 with the foot. After the engine 10 is started, the operator merely releases the foot pedal 38 and allows the small engine 14 to return to its normal position. Thus, the large engine 10 may be started by merely first starting the small engine 14, which may be easily accomplished in the usual manner, and then by depressing the foot pedal 38, whereby the rotating pulley 26 of the smaller engine will engage the fly wheel 12 and initiate the rotation thereof, whereby the large engine 10 will be started.

From the foregoing, it will be apparent that the present invention provides a simple and expedient means for starting a large engine. The large engine may be easily started by depressing a foot pedal in order to bring the friction surface of a rotating pulley into contact with the fly wheel of the large engine. The physical contact of the friction surface adjacent the fly wheel transmits rotational motion or torque to the fly wheel for starting of the engine. Thus, the present invention provides a compact unit which is simple and efficient in operation and economical and durable in construction.

Changes may be made in the combination and arrangement of parts as heretofore set forth in the specification and shown in the drawings, it being understood that any modification in the precise embodiment of the invention may be made within the scope of the following claims without departing from the spirit of the invention.

We claim:

1. A starter for a large engine having a fly wheel and comprising a base member, a small engine pivotally mounted on the base member in a manner to rotate in a plane parallel to the plane of the fly wheel, a pulley member secured to the small engine for rotation thereby, a friction surface element provided on the periphery of said pulley, and means for moving the small engine toward the fly wheel to engage the pulley with the fly wheel, said means comprising a pivotal shaft journalled in the base member, a lever member providing rotation of the shaft, and an arm member rigidly secured to the shaft for pivoting the small engine upon rotation of the shaft, said pivotal movement of the small engine in one direction causing contact between the pulley and the fly wheel, and a tapered surface provided at one end of the arm member for limiting the rotation of the shaft in said direction.

2. A starter for a large engine having a fly wheel and comprising a base member, a small engine pivotally mounted on the base member in a manner to rotate in a plane parallel to the plane of the fly wheel, a pulley member secured to the small engine for rotation thereby, a friction surface element provided on the periphery of said pulley, a transverse shaft journalled in the base member, a lever arm secured at one end of the shaft for rotation thereof, an arm member rigidly secured to the shaft and disposed substantially medial thereof, said arm member provided with a cam surface at one end thereof for rotating the small engine upon rotation of the shaft mem-

ber in a direction for providing contact of the friction element of the pulley member with the fly wheel, and a tapered surface provided at the opposite end of the arm member for limiting the rotation of the shaft in said direction.

3. A starter for a large engine having a fly wheel and comprising a small engine mounted on a channel member, said channel member pivotally secured to a base member disposed adjacent the fly wheel, a pulley connected to the small engine for rotation thereby, a friction surface element provided on the periphery of the pulley, said base member extending beyond the channel member to receive a transverse pivotal shaft, a lever member rigidly secured adjacent one end of the shaft for rotation thereof, an arm member secured to the shaft substantially medial thereof, a cam surface provided at one end of the arm to contact the channel member for pivoting the friction element of the engine toward the fly wheel upon one direction of rotation of the shaft, and means for limiting the rotation of the shaft in said direction to preclude disengagement of the cam surface and the channel member.

4. A starter for a large engine having a fly wheel and comprising a small engine mounted on a channel member, said channel member pivotally secured to a base member disposed adjacent the fly wheel, a pulley connected to the small engine for rotation thereby, a friction surface element provided on the periphery of the pulley, said base member extending beyond the channel member to receive a transverse pivotal shaft, said shaft journalled in the base member below the channel member, a lever member rigidly secured adjacent one end of the shaft for rotation thereof, an arm member secured to the shaft substantially medial thereof, a cam surface provided at one end thereof to contact the channel member for pivoting the friction element of the engine toward the fly wheel upon rotation of the shaft in one direction, and said arm provided with a tapered portion at the opposite end thereof to contact the base member for limiting the rotation of the pivotal shaft in said direction to preclude disengagement of the cam surface and the channel member.

5. A starter for a large engine having a fly wheel and comprising a base member disposed adjacent the fly wheel, transverse pivotal shafts journalled at opposite ends of the base member, a channel member secured to one of said pivotal shafts for rotation thereby, a lever arm secured to the other of said pivotal shafts for rotation thereof, an arm member rigidly secured to the second mentioned shaft, a cam surface provided at one end of the arm member to contact the channel member for rotation thereof upon rotation of the second shaft, a tapered portion provided at the opposite end of the arm member for contacting the base member to limit rotation of the second shaft in one direction, a small engine rigidly secured to the channel member for rotation therewith alternately toward and away from the fly wheel, and a friction surfaced pulley connected to the small engine for actuation thereby and adapted to contact the fly wheel upon movement of the small engine in a direction toward the fly wheel.
